UNITED STATES PATENT OFFICE

167,544

DISPLAY CONTAINER

Rudolf A. Schmidt, Flushing, N. Y.

Application May 23, 1951, Serial No. 15,288

Term of patent 14 years

(Cl. D80—1)

To all whom it may concern:

Be it known that I, Rudolf A. Schmidt, a citizen of the United States, resident of 4625-190th Street, Flushing, Long Island, county and State of New York, have invented a new, original, and ornamental Design for a Display Container, of which the following is a specification, reference being had to the accompanying drawings, forming part hereof.

In the drawings:

Fig. 1 is a top plan view of a display container, showing my new design.

Fig. 2 is a side elevational view.

Fig. 3 is a side elevational view in a collapsed position; and

Fig. 4 is a side elevational view of the side opposite that shown in Fig. 3, in a collapsed position.

I claim:

The ornamental design for a display container, as shown.

RUDOLF A. SCHMIDT.
